US00D973512S

(12) **United States Design Patent** (10) Patent No.: **US D973,512 S**
Bridges et al. (45) Date of Patent: **** Dec. 27, 2022**

(54) **BLISTER PACK**

(71) Applicant: **Gilead Sciences, Inc.**, Foster City, CA (US)

(72) Inventors: **Robert Bridges**, San Mateo, CA (US); **Joseph Cordova**, Foster City, CA (US); **Trevor Zimmermann**, Foster City, CA (US); **Caricia Catalani**, San Francisco, CA (US); **Kangil Cheon**, San Francisco, CA (US); **Hortense Caroline Agnes Desodt**, New Smyrna Beach, FL (US); **Jesse Arnold Fourt**, Menlo Park, CA (US); **Brittany Jeannette Margot**, Menlo Park, CA (US)

(73) Assignee: **GILEAD SCIENCES, INC.**, Foster City, CA (US)

(**) Term: **15 Years**

(21) Appl. No.: **29/845,306**

(22) Filed: **Jul. 6, 2022**

Related U.S. Application Data

(60) Division of application No. 29/782,459, filed on May 6, 2021, now Pat. No. Des. 960,718, which is a continuation of application No. 29/762,026, filed on Dec. 14, 2020.

(57) **CLAIM**

The ornamental design for a blister pack, as shown and described.

DESCRIPTION

FIG. 1 is a top front perspective view of a blister pack showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The dashed broken lines in the figures illustrate portions of the blister pack that form no part of the claimed design.
